COMBINED CONFECTIONERY TRAY AND MOLD

William J. Sauer, Jr., Menomonee Falls, Wis., assignor to
W. R. Grace & Co., New York, N.Y.

Filed Oct. 30, 1974, Ser. No. 519,327

Term of patent 14 years

Int. Cl. D9—03

U.S. Cl. D9—187

FIG. 1

FIG. 2

FIG. 3

FIG. 4

FIG. 5

FIG. 1 is a top perspective view of a combined confectionery tray and mold showing my new design;

FIG. 2 is a top plan view;

FIG. 3 is a side elevational view;

FIG. 4 is an end elevational view looking from the left of FIG. 3; and

FIG. 5 is a bottom plan view thereof.

I claim:

The ornamental design for a combined confectionery tray and mold, as shown.
